Attorney

UNITED STATES PATENT OFFICE.

FRANK L. DUNAWAY, OF MONTGOMERY, WEST VIRGINIA.

BRAKE FOR CAR-WHEELS.

1,198,999.

Specification of Letters Patent. Patented Sept. 19, 1916.

Application filed February 7, 1916. Serial No. 76,658.

To all whom it may concern:

Be it known that I, FRANK L. DUNAWAY, a citizen of the United States, residing at Montgomery, in the county of Fayette and State of West Virginia, have invented certain new and useful Improvements in Brakes for Car-Wheels; and I do hereby declare the following to be a full, clear, and exact description of the invention, such as will enable others skilled in the art to which it appertains to make and use the same.

My invention relates to railway rolling stock, but more particularly to brake beams and means for associating or mounting such beams upon car trucks in operative relation to the wheels thereof.

In practice the wear upon brake shoes is naturally very great, especially in freight service, and for this reason such shoes are invariably made of renewable construction. Old worn shoes are constantly being replaced by new, the aim being to make such substitution as soon as it is discovered that a shoe has worn down to or below the seven pound limit of weight. Obviously, however, this discovery can not always be made in time to prevent serious damage to the equipment, such as wearing away the entire shoe, and grinding into the brake head itself. This mutilation of brake heads frequently continues until as a consequence, the key by means of which brake shoes and heads are ordinarily interlocked, is in turn cut out, whereupon the entire brake beam occasionally falls upon the tracks below, often causing derailments and more serious accidents. To prevent such derangements and falling of brake beams, various safety devices have been resorted to with a greater or less degree of efficiency, but these as a rule are cumbersome, noisy, unsatisfactory, and expensive to maintain.

One object of the present invention, therefore, is to correct the difficulties above mentioned, by the substitution of simple, inexpensive and reliable means for supporting brake beams in operative position.

A further object is to eliminate the ordinary form of pendulum or suspension brake beam hangers with their attending and well recognized difficulties and disadvantages.

A further object is to so position brake shoes with relation to their respective car-wheels that they will wear uniformly and prevent the defects commonly known as overlapped and beveled shoes.

A further object is to insure uniformity in height above tracks of all brake beams mounted by agency of my invention.

With the foregoing and other objects and advantages in view the present invention will be hereinafter particularly described, and then pointed out by the claims following.

In the accompanying drawings which form part of this application for Letters Patent, and whereon like numerals indicate corresponding parts in the several views: Figure 1 is a side elevation of a four-wheel car truck of substantially the Bettendorf type, having my invention applied thereto. Fig. 2 is a transverse section through truck frame taken on the line 2—2 of Fig. 1, showing car wheels and tracks in dotted lines, and Fig. 3 is a relatively enlarged fragmentary view in side elevation, showing my invention in operative relation, with side frame broken away disclosing a brake head, shoe, and quadrant of a car wheel in full lines, with brake set.

Reference being had to the drawings and numerals thereon, 1 indicates a truck frame of any approved construction and material except that its web-like sides at 2, 2, are formed solid to approximately a median horizontal line, as shown by Figs. 1 and 2. The said side webs 2, 2 are broken by slots or elongated openings 3, 3 angularly arranged, as shown by Figs. 1 and 3, each of said slots being flanked by inwardly extending and correspondingly slotted bosses 4 of uniform length as clearly indicated by Fig. 2. These slots and slotted bosses with their angular arrangement are for purposes which will hereinafter appear, and the exact degree of angularity is not material, although they are pitched downward from their outer to their inner ends as shown by Fig. 1, and a very suitable angle of pitch has been found to be about $11\frac{1}{4}$ degrees, the angle of friction for metallic surfaces being about 9 degrees.

Loosely positioned within oppositely disposed slots 3, 3, and extending therethrough from side to side of the truck frame 1 is a brake-beam-hanger-bar 5. This bar is of a diameter slightly less than the width of slots 3, thereby permitting it to slide readily from end to end of its said supporting slots and is retained against longitudinal movement by end washers 6, and cotter pins 7 in the well understood manner of securing such

elements. Impaled and pivotally supported upon the said bar 5, near opposite ends thereof, are ordinary standard brake-heads 8, 8, the said rod passing completely through 5 transverse openings which in standard heads are designed to receive ordinary depending brake-beam hangers. By reference to Fig. 2 it will be observed that the slotted bosses 4 are arranged and adapted to offset the brake- 10 heads 8 and maintain them in exact vertical alinement with the car wheels 9 at all times. While within these heads 8 are detachably but firmly secured as by means of the usual key 10 an ordinary brake shoe 11, as best 15 shown by Fig. 3, and, as customary in car braking apparatus, each pair of brake heads 8, 8 are connected by an intervening brake-beam 12 of any approved construction, by agency of which power is applied.

20 This being a description of my invention in one form of embodiment it should be understood that I do not consider myself limited to the particular arrangement and combination of elements shown and described. On the contrary, these may be variously modified, changed and rearranged without in the least departing from the spirit of my invention, and to all such adaptations I lay claim the same as if herein set 25 forth.

30 The operation of my invention is as follows: When the brakes are not in action, hanger bar 5 will naturally gravitate, more or less, toward the lowermost ends of slots 3, thus withdrawing its coöperating shoes 11 from contact with the wheels 9, this automatic action being facilitated by vibration of the truck when in motion, although it will be noted that the angularity of these 35 slots is such as to insure the same results if the truck is motionless. If now, the brakes are applied by the ordinary and well understood means, the bars 5 are caused to ascend their respective slots 3 to the position indicated by Fig. 3, thereby applying brake shoes 11 evenly and uniformly to the tread surfaces of wheels 9. And it will be particularly noted that this outward movement 40 of rods 5 is positively limited by the length 50 of the said slots 3, upon reaching the ends of which further movement of the shoes 11 becomes impossible. As a consequence, shoes cannot be worn down beyond the fixed limit 55 of safety, nor can the brake heads be forced into contact with car wheels, thus obviating

two very common and serious sources of trouble.

It should also be noted that the present invention is not restricted to trucks having web-like sides 2, 2 extending upward to approximately the median line of the side frame as shown by the drawings, but is equally applicable to any frame wherein slots 3, 3, or equivalent supports for hanger rods 5, may be employed, it being within the 60 spirit of the present invention to employ properly slotted straps of iron securely bolted to side frames, such for example as Bettendorf or Vulcan frames, or other frames of skeleton form, so as to bridge any 65 openings which occur therein at points where slots 3, had best be located.

Having thus described my invention what I now claim and desire to secure by Letters Patent is:

75

1. A car truck including in combination oppositely disposed side frames, a transversely arranged hanger rod, brake shoes carried by said rod, a brake beam connecting said shoes, and slotted means associated with 80 the side frames for reciprocally mounting said hanger rod and normally retaining it in a retracted position.

2. A car truck including in combination a transversely arranged hanger rod, brake 85 shoes carried by said rod, a brake beam connecting said shoes, and oppositely disposed side frames slotted longitudinally to receive said hanger rod in sliding relation.

3. A car truck including in combination a transversely arranged hanger rod, brake 90 shoes carried by said rod, and oppositely disposed side frames slotted at an angle to their longitudinal axes to receive said hanger in sliding relation and normally retain 95 same in a retracted position.

4. A car truck including in combination a transversely arranged hanger rod, brake 100 shoes carried by said rod, and oppositely disposed side frames having bosses upon their inner faces provided with longitudinal slots to receive said hanger rod in sliding relation.

In testimony whereof I affix my signature, in presence of two subscribing witnesses.

FRANK L. DUNAWAY.
